TABLE LAMP

William Kelly, Blackpool, England

Application March 15, 1956, Serial No. 40,616

Term of patent 14 years

(Cl. D48—19)

FIG. 1.

FIG. 2.

FIG. 3

Fig. 1 is a front elevational view of a table lamp, showing my new design;

Fig. 2 is a top plan view thereof;

Fig. 3 is a rear elevational view; and

Fig. 4 is a side elevational view.

The dominant features of my new design are shown in solid lines.

I claim:

The ornamental design for a table lamp, as shown and described.
